CLAIM

The ornamental design for a lens module for automobile lamp, as shown and described.

DESCRIPTION

FIG. 1 is a front elevational view of a first embodiment of the lens module for automobile lamp, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top front left perspective view thereof;

FIG. 8 is a bottom front left perspective view thereof; and

FIG. 9 is a rear side perspective view thereof.

FIG. 10 is a front elevational view of a second embodiment of the lens module for automobile lamp, showing our new design;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a top front left perspective view thereof;

FIG. 17 is a bottom perspective view thereof; and,

FIG. 18 is a rear side perspective view thereof.
